UNITED STATES PATENT OFFICE.

SUSANNE WESTCOTT, OF COUNCIL BLUFFS, IOWA.

HOOK AND EYE.

No. 797,755.

Specification of Letters Patent.

Patented Aug. 22, 1905.

Application filed December 20, 1904. Serial No. 237,616.

To all whom it may concern:

Be it known that I, SUSANNE WESTCOTT, a citizen of the United States, residing at Council Bluffs, in the county of Pottawattamie and State of Iowa, have invented a Hook and Eye, of which the following is a specification.

This invention relates to improvements in fastening devices for garments, and more especially to the class of hooks and eyes.

The objects of the invention are to provide a hook-and-eye fastening which shall be strong and durable, can be quickly and conveniently attached to the parts of a garment, will serve to reinforce such parts, and when in use will insure a firm connection between the same.

Other objects and advantages of the invention will hereinafter appear, and what I claim as novel, and desire to secure by Letters Patent, is more specifically set forth in the appended claims.

In the accompanying drawings, which form a part of this specification, Figure 1 is a view showing my invention in the condition the same will be placed upon the market. Fig. 2 is an enlarged detail view of the hook. Fig. 3 is a similar view of the eye. Fig. 4 is a sectional view of the hook on the line 4-4 of Fig. 2.

Like letters of reference indicate like parts in all the figures of the drawings.

In carrying out my invention I make both the hook and the eye of wire and attach the same by stitching to strips of fabric or tape, as A, so that any number of such hooks and eyes may be readily attached to the meeting edges of a garment by simply sewing the strips along such edges.

The hook comprises the bill b, the shank b', the lateral extensions b² b⁴, hereinafter described, which form the attaching means, and the humps b³ in the terminal portions which lie alongside the shank. In forming this hook a suitable length of wire is employed, which is first bent together to form the bill b. Then by further bending the wire the shank b' is formed. Then the extensions b² are formed by separating the two strands or wires and bending them in opposite directions from the outer end of the shank and returning said strands or wires, as at b⁴, toward the bill of the hook, at which latter point they cross each other over the shank, as at b⁵, from which the wires extend alongside the shank, are formed into humps b³, and the free ends passed finally under b². The lateral extensions at either side of the hook and comprising the portions b² and b⁴ of the wire are bent in and out or zigzag

for their entire length, so that the hook may be attached by continuous rows of stitches, as s and s', which will engage the wire and hold it firmly to the tape or strip of fabric A. These extensions at opposite sides of the hook also provide a wide bearing for the hook and being bent in and out or zigzag provide for quickly and conveniently attaching the hook to the fabric by means of a sewing-machine instead of by hand, as is usual.

The bill b of the hook is curved inward near its end, as at b⁶, so that normally it will lie between the humps b³ of the terminal portions of the wire, and the outturned end of the bill in conjunction with the humps will provide an entrance for the eye C, which latter forms the other part of the fastening device.

It will be observed that as the humps between which the bill of the hook passes are formed on the terminal portions of the wire such humps will be permitted to yield as the eye passes in between the bill and said humps, and as the terminals or free ends of the wire pass under the extensions the same will reinforce the bill of the hook against outward strain.

The eye C is formed with lateral extensions similar to the hook—that is to say, with the curved portion c and the straight portion c², at the center of which latter the engaging eye or loop c' is formed. In forming this part of the fastening a length of wire is used and is first bent centrally to form the engaging eye or loop c', from which it is extended in opposite directions to form the straight portions c² and then bent to form the curved portions c, the free ends being brought together some distance in rear of the engaging eye or loop, as shown. Those portions of the wire which form the lateral extensions c c² are bent in and out or zigzag, as in the case of the extensions of the hook, so that this part of the fastening device may be also attached to a tape or strip of fabric by rows of stitches.

In applying the hook and eye to the tape or fabric the straight portion of the lateral extensions lie parallel with one edge of the tape or fabric, while the curved portions of said extensions extend away from said edge. By this arrangement (see Fig. 1) the straight line of stitches s secures the straight part of the extensions and the curved portions are secured by the stitches s'. This serves to securely attach the fastening devices and in

such manner that the hook will be firmly held at each end, and the eye being also firmly held the hook and eye will closely connect the parts of the garment and prevent any gapping or opening. It is also obvious that as the hook and eye are securely attached the operation of connecting the same is easily accomplished.

It is the intention to apply the hook and eye for all purposes for which such a fastening is used, and in some instances they will be made large and strong for application to horse-blankets, &c.

By attaching the hooks and eyes to strips of fabric or tape they can be more easily handled and quickly applied by simply stitching the fabric or tape to the parts to which they are to be attached.

Owing to the fact that both the hook and eye are provided with the side extensions, forming wide bearings and acting to stiffen the parts to which the fastening is applied, the device may be effectively used as a fastening for the neckbands of ladies' garments.

Having thus described my invention, what I claim as new, and desire to secure by Letters Patent, is—

1. In a fastening device, a strip of fabric or tape, a series of hooks attached thereto by continuous lines of stitches, each hook formed of wire bent to provide the bill and shank from one end of which latter the wires or strands are extended in opposite directions outward some distance from the shank, as at b^2 , and then inward, as at b^4 , to the other end of the shank, said extensions b^2, b^4 being bent in and out or zigzag to receive the continuous lines of stitches, substantially as shown and described.

2. In a fastening device, a strip of fabric or tape, a series of hooks attached thereto by continuous lines of stitches, each hook formed of wire bent to form the bill and shank and

extended at each side of the latter to provide the lateral extensions, the wire forming said extensions being bent in and out or zigzag and the terminals of the wire brought alongside the shank of the hook and passed under the extensions, and the humps formed in the terminals to receive the bill of the hook, substantially as shown and described.

3. In a fastening device, a hook made of wire and comprising the bill b formed by bending the wire together, the shank b' formed by further bending the wire, and the lateral extensions at opposite sides of the shank formed by separating the strands or wires and bending them outward some distance, as at b^2 , and then inward, as at b^4 , toward the loop end of the hook, at which latter point the wires cross each other over the shank and are extended along opposite sides of the same and finally pass under the extensions b^2 , those portions of the wire forming the extensions b^2, b^4 being bent in and out or zigzag, as shown, to receive continuous lines of stitches in attaching the device.

4. In a fastening device, a strip of fabric or tape, a series of eyes attached thereto by continuous lines of stitches, each eye formed of wire bent to provide the engaging loop, as c' , from which the wire is extended in opposite directions, as at c^2 , some distance from the engaging loop and returned, as at c , to a point in the rear of the engaging loop, said portions c^2 and c of the wire being bent in and out or zigzag to receive the continuous lines of stitches, substantially as shown and described.

In testimony whereof I have signed my name to this specification in the presence of two subscribing witnesses.

SUSANNE WESTCOTT.
